UNITED STATES PATENT OFFICE.

ADOLPH A. THOMMEN, OF CHICAGO, ILLINOIS.

BLOWER.

1,242,077.

Specification of Letters Patent. Patented Oct. 2, 1917.

Application filed September 11, 1915. Serial No. 50,199.

To all whom it may concern:

Be it known that I, ADOLPH A. THOMMEN, a citizen of the United States, residing at Chicago, in the county of Cook and State of Illinois, have invented new and useful Improvements in Blowers, of which the following is a specification.

This invention relates to improvements in blowers.

10 In carrying out the present invention it is my purpose to provide a blower which will be constructed in such manner that the air may be delivered to the rotor through the sides thereof at an angle to the path of movement of the rotor and delivered to the discharge blades under pressure and then delivered from the blower by the discharge blades under a greater pressure. It is also my purpose to provide a blower which may 15 be built on a comparatively small scale and at the same time deliver a relatively large volume of air under a high velocity.

Another object of my invention is to provide a blower which will embody comparatively few parts and these so arranged and correlated as to reduce the possibility of derangement to a minimum and operate efficiently and effectively under all conditions.

With the above and other objects in view, 20 the invention consists in the construction, combination and arrangement of parts set forth in and falling within the scope of the appended claim.

In the accompanying drawings:

25 Figure 1 is a view in side elevation of a blower constructed in accordance with my present invention.

Fig. 2 is a vertical transverse sectional view through the blower.

30 Fig. 3 is a longitudinal sectional view through the rotor removed from the casing.

Fig. 4 is an enlarged fragmentary transverse sectional view through the rotor.

35 Fig. 5 is a vertical sectional view through a modified form of the invention.

Fig. 6 is a similar view through another modified construction.

40 Fig. 7 is a like view showing a further modification.

Referring now to the drawings in detail, 45 1-1 designate substantially rectangular frames arranged vertically and spaced apart in parallelism. These frames are preferably, although not necessarily, formed of angle iron and are connected by means of

horizontal brace rods 2 disposed within the corners of the frames. Secured to the lower members of the respective frames 1-1 and projecting upwardly therefrom are standards 3-3 having the upper extremities thereof terminating short of the centers of the frames and secured to such extremities of the standards 3-3 are horizontally alining bearings 4 respectively, disposed at the centers of the frames. In the present instance, the upper extremity of each standard 3 is reinforced by means of a horizontal bar 5 extending across the frame and having the extremities thereof secured 50 to the respective side members of the frame. Secured to the inner surface of the respective frames 1-1 are side plates 6 and spanning the space between the side plates and having the opposite edges thereof fastened 55 to such plates is a semi-convoluted wall 7 having one end arranged at one side of the frames at a point in line with the axes of the bearings 4-4 and the remaining extremity disposed above the first end and 60 spaced apart therefrom to form a delivery opening. The plates 6 and the convoluted wall 7 constitute a casing and formed in the plates 6 concentrically of the bearings 4-4 are openings 8. Fastened to the inner side 65 of each plate 6 concentrically of the opening 8 therein is the relatively large end of a frusto-conical shell 9. The inner or small ends of these shells 9 are spaced apart from each other as clearly illustrated in Fig. 2 70 of the drawings, and these shells constitute inlets to the casing formed by the plates 6 and the wall 7.

Journalized in the horizontally alining bearings 4 and arranged centrally of the shells 95 9 is a shaft 10 and keyed upon the shaft 10 between the bearings 4-4 are collars 11 spaced apart a distance corresponding to the space between the inner ends of the shells 9. Suitably secured to the collars 11 and 100 radiating therefrom are discharge blades 12 appropriately spaced apart and each of a width slightly less than the distance between the inner ends of the shells. The outer ends of the discharge blades 12 terminate substantially in line with the inner extremities of the shells, while formed integral with the opposite side edges of each discharge blade 12, or otherwise connected thereto, are intake blades 13 arranged at obtuse angles to 105 the discharge blades and projecting upwardly from such blades. The blades 13

- on each discharge blade 12 are preferably of a width substantially equal to the distance between adjacent discharge blades, and formed on the upper end of each inlet blade 13 is an inwardly projecting wing 14, terminating in line with the adjacent side edges of the discharge blades, and flanged upwardly as at 15. The flanges 15 on the inner ends of the wings of the inlet blades 10 at each side of the rotor are disposed contiguous to one another and are secured together by means of a ring 16. These rings 16 are disposed in juxtaposition to the inner extremities of the shells 9—9 respectively. 15 The intake blades 13, upon each side of the rotor, project through the relatively small end of the adjacent shell 9 and into such shell.

In practice, the shaft 10 is connected up 20 with a suitable source of power so that the shaft and the rotor thereon may be revolved and, in the rotation of the rotor, the air is drawn into the shells 9 and into contact with the inner sides of the intake blades 13. 25 Owing to the positions of the intake blades relatively to the discharge blades 12, the air is directed onto the discharge blades by the intake blades under pressure and, as the air is delivered to the discharge blades, the 30 latter redeliver the air to the casing and force the same out through the discharge opening between the ends of the convoluted wall 7. It will be noted, that, owing to the 35 shape of the wall 7, the velocity of the air delivered to the casing from the discharge blades is gradually increased from the lower end of the wall 7 to the discharge opening of the casing, thereby enabling the air to be 40 discharged from the casing at a relatively high velocity.

In the modified form of my invention 45 illustrated in Fig. 5, I have shown the rotor as constructed with intake blades upon one side only and, in this form of the invention, the side of the rotor opposite the intake blades is closed by means of a circular disk 17 that projects beyond the outer ends of the blades and the projecting end of the disk co-operates with the ring 16.

50 If desired, the disk 17 may be eliminated and the edges of the discharge blades opposite the intake blades are cut inwardly toward the center of the rotor, as illustrated in Fig. 6 of the drawings. Fastened to these

inwardly cut edges of the discharge blades 55 is a frusto-conical shell 18 that acts to close the idle side of the rotor. The outer or relatively large end of the shell 18 is preferably formed with an outwardly projecting circumferential flange 19 that revolves in 60 juxtaposition to the inner end of the adjacent shell 9. In Fig. 7 of the drawings, I have shown two of these single acting rotors connected together. To fasten these single rotors together, the outer extremities of the 65 shells 18 are placed end to end and the flanges 19 thereon are bolted or otherwise connected to each other.

If desired, the intake spaces upon either side of the rotor may be of greater capacity 70 than the spaces between the discharge blades, or vice versa, the spaces between the discharge blades may have greater capacity than the intake spaces.

While I have herein shown and described 75 certain preferred forms of my invention by way of illustration, I wish it to be understood that I do not confine myself to the precise details of construction herein described and delineated, as modification and 80 variation may be made within the scope of the claim and without departing from the spirit of the invention.

I claim:—

In a blower, a casing having the side walls 85 thereof formed with round openings, a frusto-conical sleeve within each of said openings and each having its wider end secured to the walls of the openings, a shaft journaled in bearings arranged concentric 90 of the openings, a rotor upon the shaft including radially disposed blades disposed between the inner ends of the sleeves, a ring member secured to the outer edges of the 95 said central blades, said rotor further including angularly disposed intake blades also radiating from the shaft, and inclined wing members connecting the outer ends of the blades with the ring members and providing tops for the said intake blades, and said 100 intake blades being disposed within the referred to frusto-conical sleeves.

In testimony whereof I affix my signature in presence of two witnesses.

ADOLPH A. THOMMEN.
